TENS TRANSFER DEVICE

Eberhard Menge, Braunschweig, Germany, assignor to Brunsviga Maschinenwerke Aktiengesellschaft, Braunschweig, Germany

Application February 9, 1953, Serial No. 335,846

Claims priority, application Germany
February 16, 1952

7 Claims. (Cl. 235—138)

1

This invention relates to a tens transfer device with a tens transfer guiding member adapted to be engaged by radial swinging and to influence the tens transfer device in an axial direction.

It is an object of the present invention to provide a tens transfer device with one-step mode of action.

Another object of the invention is to provide a device of the type referred to which is very compact and occupies relatively small space.

Still another object of the invention is to provide a tens transfer device having relatively few constructional elements to be manufactured with high precision and small tolerance, so as to ensure a reliable operation even after long service life under exacting conditions.

With these and further objects in view, according to the present invention the head of the tens transfer guiding member is in superposition with the tens cam carrier during the rotation of the shaft of the operating mechanism and during the radial inward swinging motion of the tens transfer guiding member it moves the tens cam carrier into its operative position through direct axial action by means of an inclined control surface.

The inclined control surface may be arranged in a stationary position in relation to the machine frame, in such a way that it acts to swing the tens transfer guiding member in an axial direction during the radial inward swinging movement of the same, whereby the tens cam carrier is moved into its operative position with the aid of the head of the tens transfer guiding member with which the tens cam carrier remains in permanent superposition. The inclined control surface by which the tens cam carrier can be moved into its operative position, can also be directly arranged on a tens transfer guiding member which is only radially swingable.

Other and further objects, features and advantages of the invention will be pointed out hereinafter and appear in the appended claims forming part of the application.

In the accompanying drawings several now preferred embodiments of the invention are shown by way of illustration and not by way of limitation.

Fig. 1 is a plan view, partly in section, of the elements of a calculating machine coming into question for the tens transfer device.

Fig. 2 is a similar view, but showing the elements partly in another position.

Fig. 3 is a side view thereof, partly in section,

Fig. 4 is a plan view, partly in section, showing a second embodiment of a tens transfer device having the invention applied thereto, and

2

Fig. 5 is a plan view, partly in section, showing a still further embodiment of the tens transfer device.

Similar reference numerals denote similar parts in the different views.

Referring to Figs. 1, 2, and 3, it will be seen that four parallelly disposed shafts 2, 3, 4, and 5 are accommodated in the casing or frame 1 of a calculating machine; the shafts 2, 3 are mounted for rotation in the machine frame and serve as driving and operating mechanism shafts operatively connected to each other by the machine drive (hand crank 28 or motor) through toothed wheels 29, 30, and 31, while the shafts 4 and 5 are fixedly mounted for the rotation of totalizer wheels 6 and intermediary wheels 7 seated thereon, respectively.

Secured on the driving shaft 2 are the driving discs 8 with adjustable sprocket teeth 9 which can be set by rotatable cam discs 10 by means of curved grooves 32. Sprocket teeth 9 set into operative position on rotation of the shaft 2 through the intermediary wheels 7 cause rotative displacement of the totalizer wheels 6 which are connected with numeral wheels 12 whose axially adjusted numerals can be read off through show windows 11 in the casing 1. Each intermediary wheel 7 has a cam 13 which becomes effective for tens transfer when passing over from the "9" to the "0" or vice versa. Pin-connected to the shaft 3 of the operating or tripping mechanism is a disc 14 with a restoring cam 15 for each value denomination, adjacent to a disc-shaped tiltable tens transfer member 18 carrying two tens shift cams 16 and being acted upon by a spring 17. The tens cams 16 are each staggered from one denominational order to the following one in known manner to carry over successive tens transfers. Moreover, a shaft 19 is arranged above the transfer mechanism, parallelly to the shaft 3 of the transfer mechanism, said shaft 19 carrying a tens transfer guiding member 20 in the form of a two-armed lever for each value denomination of the setting mechanism. At its lower end this member 20 has a head 21 which remains always in a surmounted position in relation to the disk-shaped tens cam carrier 18 and is fitted on the side directed towards the tens cam 13 with an edge 22 cooperating with said cam, and on the opposite side with a bent-off portion 23 which on swinging of the tens transfer guiding member 20 cooperates with an inclined control surface 24 fixedly mounted on the frame 1 and causing the portion 23 to move the tiltable tens transfer disc 18 into the inclined position shown with respect to the upper disc 18

in Fig. 2. The rearward end of the tens transfer guiding member 20 is shaped edge-fashion so as to resiliently lock or catch the lever 20 in either of its two end positions, by cooperation with a helical spring 25. The lever 20 is mounted on shaft 19 with sufficient play or freedom to permit tilting movement of lever 20 about the line connecting its catch point on the helical spring 25 with its bearing point on shaft 19, which tilting is caused by the sliding of the bent-off portion 23 of the lever end 21 on the inclined control surface 24. In the inclined position of disc 18 one of the cams 16 of disc 18 during rotation of the transfer mechanism engages in the intermediary operating wheel 7 of the next higher value denomination and completes the tens transfer.

On completion of the tens transfer the disc 18 with its restoring cam 15 comes into action and returns the tens transfer guide lever 20 to its initial position.

In the second embodiment of the invention as per Fig. 4 the part of head 21 directed towards the tilttable disc 18 is itself provided with an inclined control surface 26 supported by a plane plate 27. If the head 21 and the incline 26 of the tens transfer guiding member 20 are moved into the position shown with respect to the upper member 21, 26 in Fig. 4, the disc 18 will be tilted and one of its transfer cams 16 on rotation of the shaft 3 of the transfer mechanism will cause advancing of the intermediary wheel 7 in the next higher value denomination by one unit (tens transfer). Then the tens transfer guiding member 20 is moved back into its initial position by the disc 14.

By way of alternative there may be used instead of the tilttable tens cam carrier 18 a carrier 33, Fig. 5, of spring steel metal which is bent into the plane of the receiving wheel 7 of the next higher value denomination by action of the head 21 of the tens transfer guiding member and on completion of the tens transfer and on return of the head 21 of the tens transfer guiding member springs back into its initial position.

The operating cams 16 are arranged in pairs on each tens transfer disc 18 and in per se known manner are arranged in two helical lines so as to be able to carry out the tens transfer passing through all orders with any direction of rotation of the operating mechanism.

In order to limit the axial movement of the tens cam carriers 18 there may be provided stops preventing tilting beyond the normal position of engagement of the carriers 18 with the totalizer wheels or intermediary wheels of the next higher value denomination of the totalizer, whereby overthrow phenomena in the totalizer are effectively prevented. These stops may be formed by the guide surfaces 24 or 27 for the tens transfer guiding member which are stationary in relation to the frame, or by the suitably arranged tens transfer guiding members 20.

While the invention has been described in detail with respect to certain now preferred examples and embodiments of the invention it will be understood by those skilled in the art after understanding the invention that various changes and modifications may be made without departing from the spirit and scope of the invention and it is intended, therefore, to cover all such changes and modifications in the appended claims.

I claim:

1. In a tens transfer device, a main frame and mounted therein an operating mechanism, a

shaft therefor, a tens cam carrier with tens cams, an inclined control surface, and a tens transfer guiding member adapted to be swung towards the tens cam carrier in a radial direction and comprising an operating head arranged in such a way as to remain in permanent superposition with the tens cam carrier and to move the tens cam carrier into its operative position as the tens transfer guiding member is swung towards the tens cam carrier, by direct axial action of the inclined control surface.

2. In a tens transfer device, a main frame and mounted therein an inclined control surface fixedly arranged on the frame, an operating mechanism, a shaft therefor, a tens cam carrier with tens cams, and a tens transfer guiding member adapted to be swung towards the tens cam carrier in a radial direction and comprising an operating head arranged in such a way as to remain in permanent superposition with the tens cam carrier and to be swung in an axial plane by cooperation with said inclined control surface as it is swung towards the tens cam carrier, whereby the latter is moved into its operative position, against spring action.

3. In a tens transfer device, a main frame and mounted therein, an operating mechanism, a shaft therefor, a tens cam carrier with tens cams, and a tens transfer guiding member adapted to be swung towards the tens cam carrier in a radial direction and comprising an inclined control surface and an operating head arranged in such a way as to remain in permanent superposition with the tens cam carrier and to move the tens cam carrier into its operative position as the tens transfer guiding member is swung towards the tens cam carrier, by direct axial action of the inclined control surface.

4. In a tens transfer device, a main frame and mounted therein an operating mechanism, a shaft therefor, a disk-shaped tens cam carrier including tens cams non-rotatably but tiltably mounted on the shaft of the operating mechanism, an inclined control surface, and a tens transfer guiding member adapted to be swung towards the tens cam carrier in a radial direction and comprising an operating head arranged in such a way as to remain in permanent superposition with the tens cam carrier and to move the tens cam carrier into its operative position as the tens transfer guiding member is swung towards the tens cam carrier, by direct axial action of the inclined control surface, against spring action.

5. In a tens transfer device, a main frame and mounted therein, an operating mechanism; a shaft therefor, a restoring cam carrier, a tens cam carrier with tens cams in the form of a spring disc secured on the restoring cam carrier, an inclined control surface, and a tens transfer guiding member adapted to be swung towards the tens cam carrier in a radial direction and comprising an operating head arranged in such a way as to remain in permanent superposition with the tens cam carrier and to move the tens cam carrier into its operative position as the tens transfer guiding member is swung towards the tens cam carrier, by direct axial action of the inclined control surface.

6. In a tens transfer device, a main frame and mounted therein an inclined control surface fixedly arranged on the frame, an operating mechanism, a shaft therefor, a tens cam carrier with tens cams, and a tens transfer guiding lever arrangement including a pivot and a catch device,

said tens transfer guiding lever being mounted on its pivot with play and having a head adapted to swing in a radial plane into its engaged position and to swing in an axial plane about the line of connection between the active point of the catch device and the pivot, under action of said inclined control surface, for swinging the tens cam carrier into its operative position.

7. In a tens transfer device, a main frame and mounted therein, a totalizer including totalizer wheels, an operating mechanism, a shaft therefor, a disk-shaped tens cam carrier including tens cams non-rotatably but tiltably mounted on the shaft of the operating mechanism, an inclined control surface, a tens transfer guiding member adapted to be swung towards the tens cam carrier in a radial direction and comprising an operating head arranged in such a way as to remain in permanent superposition with the tens cam car-

rier and to move the tens cam carrier into its operative position as the tens transfer guiding member is swung towards the tens cam carrier, by direct axial action of the inclined control surface, and stops for preventing the tens cam carrier from tilting beyond the normal position of engagement with the wheels of the next higher denomination of the totalizer.
